UNITED STATES PATENT OFFICE.

ALEXANDER F. SWEEDEN, OF LONG ISLAND CITY, NEW YORK.

FEEDING, SORTING, AND COLLECTING MECHANISM.

Application filed April 26, 1921. Serial No. 464,756.

To all whom it may concern:

Be it known that I, ALEXANDER F. SWEEDEN, citizen of the United States, and resident of Long Island City, in the county of 5 Queens and State of New York, have invented certain new and useful Improvements in Feeding, Sorting, and Collecting Mechanism, of which the following is a specification.

10 This invention relates generally to article separating and feeding mechanism. I do not wish to limit myself to the use to which my invention can be put, but for the purpose of a clear understanding, will specifically describe its adaptation to the handling and translation of candy confections such as lozenges, wafers, disks and like or other articles and for separating articles of one size from those of another size, or 20 broken articles from whole ones, so that should my mechanism be used in connection with package filling machines, the work of dispatching intact or whole candies or articles, as the case may be, from a suitable hopper or container to a point where their discharge is desired, labor will be facilitated and considerable time saved in delivering articles which are uniformly of the same size and shape to the said point where their 30 use is desired.

Candy confections of the kind above specified are usually vended in elongated packages and use is generally made of a suitable filling machine for supplying the 35 package with a predetermined number of candies. In order to facilitate the operation of filling such packages, the candies are fed from a source of some description to the point where the filling operation is conducted. Frequently and due to the fragile 40 nature of the candies, the latter are broken by the time they reach the packages, cartons or containers and it then becomes necessary that the broken ones be manually as- 45 sorted or separated from the whole ones with which the packages are to be supplied. Considerable time and expense are incurred in properly separating the candies, incident to the reasons above advanced, and it is 50 therefore an object of my invention to entirely eliminate this waste and loss of money and provide a mechanism which will be automatic of operation; one which will allow for a maximum handling of the candies in their progress from a supply source 55

to an active delivery point or position; one which will be simple of construction and positive of action under many trying conditions, and one wherein means are employed for rendering the separating or as- 60 sorting operation absolutely reliable.

A still further object of my invention is to provide a feeding and separating or assorting mechanism which will operate upon candies when placed in bulk or large quantities in a hopper or the like, without any regard to likeness of the candies in shape or size to one another, and positively segregate those of one kind or shape from those of another, means being employed for checking the separating operation so that should some broken or imperfect candies remain in the mechanism after a preliminary separation thereof, a final separation will be advanced to insure the delivery of nothing 70 but candies of the same uniform size and shape from the mechanism.

Another object of the invention is to provide a mechanism of the class described which will be characterized by a collector 80 which operates in a hopper to pick up quantities of candies and discharge the collected candies intermittently and in timed regularity.

A further object of the invention is to 85 provide a mechanism which is particularly characterized by a revolving collector which is constructed so that it may be used in connection with a co-acting hopper or receptacle wherein the candies to be separated and distributed are carelessly or indiscriminately placed, the collector operating to pick up the candies and uniformly arrange the same and distribute them in row formation from the mechanism. 90

95 Other important features will be referred to hereinafter and the invention defined in the claims.

Reference is now had to the accompanying drawings which represent, as an example, the preferred embodiment of my invention, in which drawings:—

100 Figure 1 is a plan view of the mechanism.

Figure 2 is a section therethrough taken on the line 2—2 of Figure 1.

Figure 3 is a section taken on the line 3—3 of Figure 1.

Figure 4 is a front elevation of the combined collecting and distributing disk.

Figure 5 is a section similar to Figure 3 110

showing an unbroken confection in the slot.

Figure 6 is a cross section of the run-way.

In carrying the invention into practice, I use a disk 10, preferably mounting the same 5 on a shaft 11. The said disk is disposed within a hopper 12 and the base of the latter opens directly onto one of the flat faces of said disk. The disk is arranged at an obtuse angle to a line drawn horizontally through 10 the hopper. Arranged in what I will call the working or active face 13 of the disk are straight recesses or pockets 14. The mentioned recesses or pockets are arranged at a tangent to the shaft 11 and their outer ends 15 open onto the periphery of the disk at equidistant points thereabout. The bottom wall 15 of the hopper slants downward toward the active face of the disk and the same is located immediately above the base of the 20 disk so that the entire portion of each recess will be exposed to the full depth of the hopper as the disk is rotated. The general arrangement of the parts is such that articles when placed in the hopper will gravitate to said working face of the disk, and as 25 the latter revolves in the direction of the arrow in Figure 1, said articles are picked up by said recesses or pockets 14.

The walls 16 of the recesses or pockets are 30 provided with slots 17, the same extending for the full length of said recesses and opening onto the inactive face 18 of the disk. As stated, the mechanism is designed for use in connection with package filling machines 35 wherein disk like candies constitute the contents of said packages. Such candy disks are dumped into the hopper 12 and incident to the inclination of the disk 10 and the rotary action of said disk, the candies are agitated and collected by the disk and received flat wise in the recesses or pockets 14. As 40 the disk revolves, the recesses or pockets are successively presented to the hopper, the slots 17 lying uppermost. Upon further rotation of the disk, the position of the slots 45 17 change and successively the recesses are presented at downward angles toward the left wall 19 of the hopper. In partial rotation of the disk between the base of the hopper and the left wall 19 of the hopper, the slots 50 gradually become inverse to the mentioned uppermost positions which the slots occupy when the recesses first enter the base 55 of the hopper. This change in the positions of the slots causes any broken candy to fall through said slots and pass into a receiving chute 20. From the chute 20 the broken particles may be conducted off to a waste 60 receptacle, (not shown). This operation of the mechanism is made positive through the fact that the disk 10 extends upward and rearward from the bottom of the hopper, and the said broken candy is permitted to 65 drop by gravity into said chute 20. The

slots 17 are relatively narrow as compared with the transverse dimensions of the recesses or pockets so that the whole candies will be supported by the walls 16 and held against passing through said slots.

The left half of the working face of the disk 10 is covered by a fixed guard plate 21 which serves to prevent the collected candies from falling back into the hopper as the disk revolves. The right half of the inactive 75 or rear face of the disk is covered by a similar fixed plate 22 which operates to prevent the candies from falling through the slots 17 until the recesses progressively pass to the left side of the mechanism above the supporting shaft 11.

Arranged in line with the periphery of the disk 10 and located at a point below the plane of the shaft 11 is a run-way 23, the same consisting of two spaced substantially U-shaped members 24-24. The grooves 25 of the members are very shallow so that only slight hold of its walls is had against the edges of the candies as the same roll or gravitate in said run-way. From this arrangement, it results that should any broken candies pass into the run-way, they will fall through the space between said members 24-24, the whole candies proceeding downward the run-way to the point where their delivery is desired. The run-way is disposed parallel to the plane of the disk 10 so that the candies are maintained in tilted positions during their movements down the mentioned run-way.

The shaft 11 is provided with a gear wheel 25 which co-acts with an intermittent gear 26. This gives the disk 10 a step by step motion and by properly spacing the recesses or pockets 14 with respect to one another, the latter are made to singly register with said run-away 23. This intermittent motion of the disk 10 is so regulated that the entire contents of each recess or pocket is delivered to the run-way as said pockets are successively registered therewith.

As previously stated, the mechanism is particularly adapted for the sorting or separating of candies of the kind stated, but it will be understood that various changes may be made within the scope of the hereto annexed claims without departing from the spirit of the invention. I want it to be understood that the mechanism is broadly useful as a separating or sorting and feeding means and that I have specifically stated one of its uses so that the operation of the invention is clear and concise so far as the construction and functioning of the invention are concerned.

What is claimed as new is:

1. A hopper, an inclined disk, co-acting with said hopper and provided with means for effecting a collection of articles from

the hopper, and a peripheral discharge of the collected articles from the disk and means for revolving said disk.

2. A hopper, a rotary disk co-acting therewith and provided with collection means for the successive collection in row formation of articles from the hopper; said disk also co-acting with the hopper to cause the articles collected by said disk to be discharged 10 from periphery thereof and through one side of the hopper, and means for revolving said disk.

3. A hopper, a rotary disk co-acting therewith and provided with collection 15 means presentable to the hopper as the disk revolves, and serving when the disk is in one position to effect a peripheral discharge of the collected articles therefrom and means for revolving said disk intermittently.

20 4. A hopper, a rotary disk co-acting therewith and provided with collection means including separated portions for successive collection in row formation of articles from the hopper and actively presentable to the 25 hopper as the disk revolves, and serving to cause the articles collected by the disk to be discharged from the periphery thereof, means for revolving said disk intermittently and a run way registering with the collection 30 means through intermittent rotation of said disk whereby to receive the peripherally discharged articles from the disk.

5. A hopper, a rotary disk co-acting with the hopper and provided with means for translating articles from the hopper to a receiving means, the translating means having portions each respectively acting to collect the articles from the hopper and temporarily retain same in row formation on 35 the disk and finally discharge same from the disk, and means for revolving the disk intermittently.

6. A mechanism of the class described, comprising a hopper, a revolving collection 45 and distributing disk co-acting with the hopper, and means on the disk for collecting articles from the hopper and for arranging the collected articles in separated grouped formation upon the disk and for effecting a 50 peripheral discharge of the collected articles from said disk as the latter is revolved.

7. A mechanism of the class described, comprising a hopper, a revolving collecting and distributing disk co-acting with the 55 hopper, means on the disk for collecting articles from the hopper and for arranging the collected articles in separated grouped formation upon the disk and for effecting a peripheral discharge of the collected articles 60 from said disk and means for revolving the disk intermittently.

8. A candy collecting, separating and distributing mechanism comprising a hopper, a revolving collecting disk co-acting with 65 said hopper, to receive candies therefrom as

the disk revolves, and subsequently discharge the collected candies from the periphery of the disk, a chute co-acting with the disk for the transfer of the discharged candies from the latter, and a sorting 70 means between the hopper and the chute, the disk having separated article collecting recesses to effect said receiving and transferring operations and for arranging the collected articles in row formation upon said 75 disk.

9. A hopper, a rotary disk co-acting with the hopper and provided with a pocket serving to pick up articles from the hopper and arrange the articles in row formation upon 80 the disk; and then discharge same therefrom, means on the disk for relieving the same of articles of sizes less than the approximate width of said pocket, and means for revolving the disk intermittently, so as 85 to place the disk at rest and permit all of the collected articles contained in the pocket to be automatically discharged therefrom.

10. A hopper, a disk co-acting with the hopper, said disk having a plurality of pockets therein arranged substantially at a tangent to the center of the disk, the disk having slots in communication with said pockets, means for partly closing one side of the disk, means for partly closing the opposite 90 side of the disk at a point laterally to one side of the first said closing means, means for intermittently revolving the disk, means adapted to register with the pockets successively and acting as a receiver for articles 95 discharged from the disk, and a chute adapted to communicate with said slots, all as and for the purpose set forth.

11. A hopper, a rotary disk co-acting with the hopper and provided with a pocket respectively serving to pick up articles from the hopper and discharge same therefrom, means on the disk for relieving the same of collected articles of sizes less than the approximate width of said pocket, means for 105 intermittently revolving the disk, and an article receiving means registering with the pocket in one position of rest of the disk.

12. A hopper, a revolving disk mounted in the hopper at an angle other than a right 110 angle to the vertical axis thereof and provided with recesses opening at their outer ends onto the periphery of the disk and serving while the disk is in rotation to pick up articles from the hopper, and means for 115 revolving the disk intermittently to successively present said recesses to a receiving means at one side of said hopper.

13. A hopper, a revolving disk mounted in the hopper at an angle other than a right 120 angle to the vertical axis thereof and provided with recesses opening at their outer ends onto the periphery of the disk and serving while the disk is in rotation to pick up articles from the hopper, means for revolv- 125

ing the disk intermittently to successively present said recesses to a receiving means at one side of said hopper, the recesses communicating with restricted slots formed in the disk and extending onto the rear side thereof.

14. A hopper, a revolving disk mounted in the hopper at an angle other than a right angle to the vertical axis thereof and provided with recesses opening at their outer ends onto the periphery of the disk and serving while the disk is in rotation to pick up

articles from the hopper, means of revolving the disk intermittently to successively present said recesses to a receiving means 15 at one side of said hopper, the recesses communicating with restricted slots formed in the disk and extending onto the rear side thereof, and plates fixed within the hopper and between which the disk is interposed 20 and respectively arranged at opposite sides of the center of said disk.

ALEXANDER F. SWEEDEN.
